BY *Robert H. Bain*,
ATTORNEY

UNITED STATES PATENT OFFICE.

B D LENHART ELLISON, OF EASLEY, SOUTH CAROLINA, ASSIGNOR TO DRAPER CORPORATION, OF HOPEDALE, MASSACHUSETTS, A CORPORATION OF MAINE.

SHUTTLE.

Application filed June 11, 1924. Serial No. 719,334.

To all whom it may concern:

Be it known that I, B D LENHART ELLISON, a citizen of the United States, residing at Easley, in the county of Pickens 5 and State of South Carolina, have invented an Improvement in Shuttles, of which the following description, in connection with the accompanying drawings, is a specification, like characters on the drawings representing like parts.

This invention relates to means for holding a bobbin within a shuttle, and more particularly to means for firmly securing the bobbin holding spring in place within 15 the shuttle.

In different types of shuttles, and more particularly in the filling replenishing type, a shuttle spring having a pair of spaced jaws is employed to engage the head of a 20 bobbin and hold the bobbin in place in the bobbin receiving opening. This spring usually constitutes the sole means for maintaining the bobbin in place during the 25 operation of the shuttle and is therefore constructed to grip the bobbin head with considerable force. As a result, the spring is subjected to a pronounced displacing force when a bobbin head is inserted between the 30 jaws or removed therefrom, and this is particularly true in the filling replenishing type of shuttle in which the new bobbin is forced downwardly rapidly between the jaws and forces the old bobbin out through the opening in the bottom of the shuttle.

It is essential that the bobbin holding spring be secured rigidly in place within 35 the shuttle, for if it is displaced only slightly by the repeated force that introduces bobbins between its jaws, it will support the bobbins 40 in an inclined position, and if a bobbin protrudes from either side of the shuttle it will break the warp threads.

Various means have been proposed for 45 securing the bobbin holding spring in place within its shuttle, and the present invention relates to novel means for firmly securing this spring in place.

The improvement of the present invention is illustrated in the accompanying 50 drawings, in which:—

Fig. 1 is a perspective view of the bobbin holding end of a shuttle with the bobbin

engaging spring and associated parts shown in disassembled relation;

Fig. 2 is a vertical sectional view through 55 the shuttle of Fig. 1 showing the shuttle holding spring in side view; and

Fig. 3 is a top plan view of Fig. 2.

The shuttle 10 may be constructed as usual and has a bobbin receiving opening 11 60 in which the bobbin 12 is supported by a bobbin engaging spring 13. This spring usually consists of a shank portion 14 to which the jaws 15 are connected by the outwardly flaring portions 16, and in the 65 construction shown the entire spring is bent from a single piece of metal folded to form the shanks that are spaced slightly and which are connected to the respective jaws by the outwardly flaring portions. This 70 shank portion 14 of the spring fits snugly into a slot 17 of the shuttle, as usual, and the spaced jaws 15 lie within the bobbin receiving opening 11.

Cooperating with the shuttle spring 13 is 75 the usual shuttle spring guard 18 having the bottom plate 19 that rests upon the bottom wall of the shuttle, and the plate 19 forms a base upon which the spring 13 is seated. The guard 18 has an integral top 80 plate 20 connected to the bottom plate 19 by the inclined wall 21, and the top plate 20 has an aperture for a screw 22 that secures it to the body of the shuttle over the spring. A spreader 23 is mounted 85 between the spaced shanks of the spring 13 and is shown as formed of sheet metal having an upper horizontally extending portion and a lower horizontally extending portion connected by an inclined portion, and the 90 lower portion of the spreader is provided with an upturned end 24 that engages a securing bolt to be described, while the upper portion of the spreader has laterally extending arms 25 that extend between the 95 guard 18 and the upper face of the spring 13.

As above pointed out, it is essential that the bobbin holding spring 13 be held rigidly in place within the shuttle, and improved 100 means for securing the spring 13 firmly in place will now be described.

Heretofore a bolt or bolts extending transversely of the shuttle and passing through

the shank portion of the bobbin engaging spring have been provided to hold the bobbin spring in place, but such construction will not prevent the spring from tilting 5 downwardly, nor will it prevent the spring 13 from tilting upwardly should the guard yield in an upward direction.

To increase the rigidity with which the bobbin engaging spring is secured in place, 10 the present invention contemplates a second transverse securing means located nearer the bobbin supporting portions of the spring jaws than the bolt heretofore employed and which preferably extends through the walls 15 of the shuttle into supporting engagement with the spring at a point between the shank portion and the bobbin receiving end of the spring.

In the construction shown the spring 13 20 is primarily secured in place by a transversely extending bolt 26 that extends through the side walls of the shuttle and through an aperture in the shank 14 of the spring, and the bolt is held in place by the 25 nut 27. The second transverse securing means for the spring may well take the form of a second bolt 28 which is positioned to extend through the side walls of the shuttle and through apertures in the flaring portions 30 of the spring which are located beyond the shank portion 14. The bolt 28 is shown as passing through alined apertures of the openings formed in the outwardly flaring portions 16 of the spring, 35 and it will be apparent that the bolt 28, to afford the maximum support, should be located as close to the bobbin engaging por-

tion of the spring as other conditions will permit. The bolt 28 is held in place by a 40 nut 29.

What is claimed is:

1. In a filling replenishing loom shuttle, the combination of bobbin holding springs comprising a shank portion and two spaced 45 bobbin holding jaws connected to the shank portion by outwardly flaring portions, a through-bolt passing transversely through the sides of the shuttle and shank portion of the bobbin holding springs for securing the parts together, and a through-bolt passing transversely through the sides of the shuttle and through the flaring portions of the bobbin holding jaws for individually 50 supporting the jaws against displacement by an incoming bobbin during replenishment of filling.

2. A filling replenishing loom shuttle having a bobbin chamber, bobbin holding springs comprising a shank portion and two spaced bobbin holding jaws having outwardly flaring portions each provided with an opening, a through-bolt passing transversely through the shuttle and shank for securing the bobbin holding springs to the shuttle, and a bolt passing transversely of the shuttle through the openings in the flaring portions of the bobbin holding jaws for preventing downward displacement of either bobbin holding jaw by an incoming bobbin 65 during replenishment of filling.

In testimony whereof, I have signed my name to this specification.

B D LENHART ELLISON.
